UNITED STATES PATENT OFFICE.

HENRY G. THOMPSON, OF CLEVELAND, OHIO, ASSIGNOR OF ONE-HALF TO THE A. C. WILLIAMS COMPANY, OF RAVENNA, OHIO, A CORPORATION OF OHIO.

DESIGN FOR A TOY BANK.

48,620.

Specification for Design.

Patented Feb. 22, 1916.

Application filed December 11, 1915. Serial No. 66,380. Term of patent 14 years.

To all whom it may concern:

Be it known that I, HENRY G. THOMPSON, a citizen of the United States, residing at Cleveland, in the county of Cuyahoga and State of Ohio, have invented a new, useful and ornamental Design for Toy Banks, of which the following is a specification, reference being had to the accompanying drawing, forming part thereof.

The figure is a perspective of a toy bank, showing my new design.

I claim:

The ornamental design for a toy bank, as shown.

H. G. THOMPSON.
